HOLDER FOR TAGS, ETC.

Levi N. Plante, Worcester, Mass., assignor to Progressive Tool & Die Company, Incorporated, Worcester, Mass., a Corporation of Massachusetts

Application April 25, 1932. Serial No. 607,257

3 Claims. (Cl. 40—11)

This invention relates to a support of the vacuum cup type adapted to be held by the vacuum cup on a window and particularly on a windshield of an automobile or any other desired place.

The principal objects of the invention are to provide such a support with means for holding a card or tag projecting upwardly or in any other desired direction and with a hook on the opposite side on which an article or card can be hung; to provide a construction in which the means for supporting the two articles constitute a single element; to provide an improved way of holding the said element on the vacuum cup and to provide means whereby the operation of the hook can be employed to open a spring grip for receiving the first mentioned card.

Other objects and advantages of the invention will appear hereinafter.

Reference is to be had to the accompanying drawing, in which

Fig. 1 is a front elevation of a preferred embodiment of the invention shown as holding two articles and in position on a smooth surface;

Fig. 2 is a central sectional view of the vacuum cup showing the holding element in elevation, and

Fig. 3 is a sectional view on the line 3—3 of Fig. 2, showing how the wire holding element is supported by the vacuum cup.

The supporting means for the device is shown in the form of a vacuum cup 10 adapted to be applied to any smooth surface in the usual way.

This cup has a head 11 of solid rubber and under this head is a neck 12 which is sunk inwardly to provide an annular groove for holding the other element of the device.

The holding element consists of a wire holder

14 provided with an arcuate end 15 making considerably more than half a circle and located in the neck 12. Both sides of the wire will be in engagement with the soft rubber on account of the fact that this neck groove is sunk in so deeply. The groove around the vacuum cup under this head is made narrower than the thickness of the wire so that the wire will be held firmly in this groove. It is difficult to turn it to a different position on the vacuum cup and when once applied it is intended to be firmly fixed and not movable.

The wire member has a coil spring 16 integral with it, preferably of two coils but it could be made of any desired number, above one. Down from the end of the last coil extends an arm 17

of the same piece of wire and at the bottom it is provided with a hook 18. On this hook can be hung a card or other article having a hole through it for receiving the hook.

The spring has two coils, at least at the top, 60 and the hook extends from the outer one. By bending the hook in, as shown in dotted lines in Fig. 2, these coils are separated from each other so that a card 20 at the top can be inserted as indicated. When the hook is released 65 from this pressure the coils of the spring pinch the bottom of the card firmly and hold it in position until it is released by the flexing in of the hook 18 again. This hook, although having an abrupt square end, will be pressed against the 70 base of the vacuum cup if it is pressed in too far and no damage will be done. The hook is shown as supporting a card 21 below.

Although I have illustrated and described only one form of the invention I am aware of 75 the fact that modifications can be made therein by any person skilled in the art without departing from the scope of the invention as expressed in the claims. Therefore, I do not wish to be limited in this respect but what I do claim is:— 80

1. As an article of manufacture, a holder for displaying an article comprising means by which it can be attached to a surface, a wire fixedly supported at one end by said means and projecting upwardly therefrom, said wire having a 85 coiled spring comprising at least two coils of wire at the top in planes substantially parallel to said surface and spaced above said surface, and an arm projecting from one coil of said spring diametrically across said means and 90 spaced therefrom to provide a free end by which the spring can be opened to facilitate application or removal of a thin object between the coils of the spring.

2. As an article of manufacture, a holder for 95 more than one article comprising a vacuum cup for securing it to a vertical surface, said cup having a head with an annular neck under the head and a holding member of wire having an arcuate portion at one end throughout more 100 than a half circle adapted to be applied to the vacuum cup by locating it in said neck, the diameter of the wire being greater than the normal width of said groove or neck, the wire 105 comprising coils constituting a spring for grasping a thin article and having from the opposite end of the coil a projecting arm having a hook at the end, said hook constituting means by 110 which the coils of the said spring can be opened

to facilitate the removal or insertion of a card or the like.

3. As an article of manufacture, a holder for more than one article comprising a vacuum cup 5 for securing it to a vertical surface, said cup being composed entirely of soft rubber having a solid head with an annular neck under the head and a supporting member consisting of a single piece of wire of the same size throughout having 10 an arcuate portion at one end adapted to be

applied to the vacuum cup by locating it in said neck, the wire extending upwardly and comprising coils constituting a spring for supporting a thin article and having from the opposite end of the coil an arm projecting outwardly and downwardly and having a hook at the bottom projecting inwardly toward the vacuum cup, said hook constituting means by which a second article can be supported. 80
